CLAIM

The ornamental design for a drink cooler as shown and described.

DESCRIPTION

FIG. 1 is a top front-left perspective view of a first embodiment of the drink cooler of the present invention;

FIG. 2 is a bottom front-left perspective view thereof;

FIG. 3 is a right side view thereof;

FIG. 4 is a left side view thereof;

FIG. 5 is a front view thereof;

FIG. 6 is a back side view thereof;

FIG. 7 is a top view thereof; and,

FIG. 8 is a bottom view thereof.

The portions of the drink cooler illustrated in broken lines form no part of the claimed design.
